[57] **CLAIM**

The ornamental design for a nasal mask, as shown and
described.

DESCRIPTION

FIG. 1 is a perspective view of the nasal mask;
FIG. 2 is a front elevational view thereof;
FIG. 3 is a right side elevational view thereof, the left side
elevational view being a mirror image thereto;
FIG. 4 is a back elevational view thereof;
FIG. 5 is a top plan view thereof;
FIG. 6 is a bottom plan view thereof; and,
FIG. 7 is a perspective view thereof, the broken line showing
is for illustrative purposes only and forms no part of the
claimed design.
